ATTORNEY.

UNITED STATES PATENT OFFICE.

MAXWELL MCNUTT, OF SAN FRANCISCO, CALIFORNIA.

SAFETY CARRIAGE-POLE AND NECK-YOKE.

SPECIFICATION forming part of Letters Patent No. 710,501, dated October 7, 1902.

Application filed January 10, 1902. Serial No. 89,158. (No model.)

To all whom it may concern:

Be it known that I, MAXWELL MCNUTT, a citizen of the United States, residing at San Francisco, in the county of San Francisco and 5 State of California, have invented certain new and useful Improvements in Safety Carriage-Poles and Neck-Yokes, of which the following is a specification.

My invention relates to an improved safety carriage-pole and neck-yoke, the object of my invention being to provide a construction thereof which will give increased safety to the occupants of the carriage in case of breakage of the tugs or whiffletrees and which will 15 absolutely prevent the neck-yoke separating from the pole of the carriage if one pair of tugs or the corresponding singletree breaks.

A further object is to provide a construction for this purpose which will be simple, inexpensive, and easily assembled, inconspicuous, presenting substantially no difference in appearance from the constructions now generally in use.

My invention, therefore, resides in the novel 25 construction, combination, and arrangement of parts for the above ends hereinafter fully specified, and particularly pointed out in the claim.

In the accompanying drawings, Figure 1 is 30 a perspective view of my improved carriage-pole and the neck-yoke thereon. Fig. 2 is a front view of my improved neck-yoke detached on a larger scale. Fig. 3 is a perspective view of the pole-tip on a still larger 35 scale. Fig. 4 is an enlarged perspective view of my improved neck-yoke leather. Fig. 5 is a similar view of the iron plate of said leather detached therefrom, and Fig. 6 is a section on the line A A of Fig. 4.

Referring to the drawings, 1 represents a 40 carriage-pole of the ordinary construction, having on the front end thereof the pole-tip 2. Said pole-tip has formed thereon in the usual manner the flange 3 for backing the carriage, and in front of said flange it has formed on its under side the elongated lug 4.

5 represents the neck-yoke, having secured thereon the neck-yoke leather 6. This is formed of a single piece of leather bent around 45 at its middle portion to form a loop or eye 7, encircling the neck-yoke 5, its terminal portions 8 being brought opposite to each other

and having secured between them the iron plate 9. Said terminal portions 8 of the leather and said plate 9 have formed there- 55 through apertures 10, all of the same shape and registering with each other, each aperture being in general of a circular form and of a size to fit around the pole-tip between the lug and the flange, but having also on the 60 side thereof extending toward the loop or eye an extension of sufficient depth to pass under the downwardly-extending lug 4 on the pole- tip 2. The edges of the two terminal portions of the leather behind the edges of the iron 65 plate 9 are secured together by lines of stitching 12. Thus the iron plate 9 is completely hidden from sight, while yet assisting by its rigidity and strength in preventing the leather being pulled forward past the lug 4. 70

It will readily be seen that the neck-yoke can be secured upon the pole by passing the same backward thereon, with the neck-yoke under the pole-tip and so that the extension 11 of the hole in the neck-yoke leather is in 75 alinement with the lug 4. Then as the neck- yoke is passed backward the lug will readily pass through said extension 11. When the neck-yoke has been passed behind the lug in this manner, it is given half a revolution 80 about the pole, which brings said neck-yoke to a transverse position above the pole, and in this position the neck-yoke is evidently securely locked against removal from the pole by the abutment of the lug 4 against the ring 85 portion 8 of the leather.

This construction is inexpensive and the parts are easily assembled. At the same time it affords greater security to the occupants of the carriage. With neck-yokes as at present 90 constructed and in use if the tugs break the neck-yoke can slip forward from the pole, which thereupon drops to the ground, the effect of which may be to upset the vehicle or to injure the occupants by striking them with 95 the pole. Also with present constructions the neck-yoke can separate from the pole, even when only one pair of tugs or one singletree breaks, the result being that the horse thus released goes in front of the other horse, tending 100 to upset the vehicle. With my improved construction these dangers are avoided.

I claim—

In a device of the character described, the

combination of a pole having a lug on the under side thereof, and a neck-yoke having a leather secured thereon, said leather being formed of a single piece, bent around at its middle portion to form a loop encircling the neck-yoke, its terminal portions being brought opposite to each other and having secured between them an iron plate, said terminal portions of leather and said plate having formed therethrough apertures all of the same shape and registering with each other, each aperture being of a size to fit around the pole-tip between the lug and the flange and having also on the side thereof extending to-

ward the loop an extension of sufficient depth 15 to pass under the downwardly-extending lug, the edges of said terminal portions on the outer side and at the aperture extending beyond the edges of the iron plate and being secured together to completely inclose said 20 iron plate, substantially as described.

In witness whereof I have hereunto set my hand in the presence of two subscribing witnesses.

MAXWELL McNUTT.
